MILLER REESE HUTCHISON, OF WEST ORANGE, NEW JERSEY.

MOTOR-STARTING MECHANISM.

1,306,183.

Specification of Letters Patent. Patented June 10, 1919.

Application filed January 4, 1918. Serial No. 210,395.

To all whom it may concern:

Be it known that I, MILLER REESE HUTCHISON, a citizen of the United States, and resident of West Orange, in the county of Essex and State of New Jersey, have invented certain new and useful Improvements in Motor-Starting Mechanism, of which the following is a specification.

My present invention relates to starting and re-starting apparatus for motor vehicles having internal combustion motors and more particularly to the class of motor vehicles of which the aeroplane is an example, although it includes certain features which 10 are applicable to other internal combustion motors particularly large or high power motors intended for various intermittent uses, as for instance, aeroplanes, trucks, automobiles, etc., where the power of the motor 15 is frequently applied to drive the vehicle or other load up an incline against gravity, the vehicle then being permitted to glide or coast downward under the influence of gravity with the motor shut off but still 20 connected to the propelling mechanism so that the motor is driven by the propelling mechanism instead of vice versa. The well-known electric motor-storage battery starters would have to be very powerful to operate satisfactorily on the larger motors and 25 hence are not used on aeroplanes because of their excessive weight, nor on trucks because of the expense.

In the case of aeroplanes, the downward 30 glides and dives by gravity cover enormous distances and the speeds attainable by gravity alone are so great that continued motor propulsion would be dangerous yet, in the aeroplane, the propeller is usually directly 35 connected to the crank shaft and throttling down is not adequate or reliable. Hence it is customary for the operator to shut off his motor completely under such conditions, thus making it necessary to re-start the 40 motor if the flight is to be continued after the end of the glide or dive. At present the only way of accomplishing this is to depend upon head pressure of the air upon the propeller keeping up the spin of the crank 45 shaft and motor. Hence when an aeroplane is aloft and the operator cuts off the motor to volplane, it is sometimes necessary to take a vertical dive of hundreds of feet in order to get sufficient air pressure against 50 the propeller to spin the engine to the desired speed. Sometimes there is not room to

take such a dive and sometimes the engine refuses to spin and in such case the operator is forced to land forthwith, often times in enemy territory and always at great danger 60 to himself because he has no opportunity to select a safe landing field.

If he makes a safe landing it is then necessary for the operator to stand in front of the aeroplane and crank the motor using the 65 propeller as a lever. This is a dangerous operation even when starting out with a cold motor, but it is much more dangerous when re-starting after alighting because of the danger of pre-ignition from the hot engine. 70 Many fatalities have occurred from this cause.

The preferred embodiment of my invention is therefore a self-starting and re-starting aeroplane having an auxiliary internal 75 combustion motor, preferably of small size and preferably air cooled, adapted to be connected in operative relation to the main propelling motor to drive the latter at or above its starting speed.

Where the auxiliary motor is small, I employ power multiplying, speed reducing gearing. As the auxiliary motor will be turning at relatively high speed when turning the main motor at slow speed, I provide 85 an over-running clutch or disconnecting mechanism such as a centrifugally controlled speed limit clutch to prevent the main motor from driving the auxiliary motor through the multiplying gear at speeds which would 90 be dangerous to the auxiliary motor.

It is desirable, however, that the two motors be connected in reciprocal driving relation so that the propeller shaft of the main motor can be utilized to drive the auxiliary 95 motor at a speed sufficient to start it. A convenient way to do this is to have two sets of power transmitting gearing each provided with overrunning clutches, the clutch in the multiplying gearing being adapted to 100 grip when the auxiliary motor acts as the driver and another gearing of less ratio or even a reducing ratio to grip when the direction of power transmission is reversed and the auxiliary motor becomes the driven member. 105

With such an arrangement, the main propelling motor may be operated either simultaneously or alternately with the auxiliary motor. In case of glides and dives the auxiliary motor may be started by the main 110 propelling motor before the latter is shut off for the glide or dive. The auxiliary mo-

- tor will then assist the propeller in keeping the main motor spinning at the desired speed, without contributing appreciable propelling power such as might dangerously increase the gliding or diving speed of the aeroplane. Then when the operator again desires to proceed on a level or resume climbing, the main propelling motor being positively driven by the auxiliary motor at a safe starting speed, can be turned on again without the necessity of steep dives to spin the motor through the propeller and without requiring the operator to exercise care or skill in timing his re-starting with reference to the speed of his dive.
- The auxiliary motor being of relatively small power, it becomes feasible to employ a small friction clutch to throw the latter into and out of operative relation to the propeller shaft without adding materially to the weight of the machine. This makes it possible to start the auxiliary motor by hand and then throw in the clutch to start the main motor, when first starting out on a trip, or whenever for any reason, it has become necessary to shut off both motors at the same time.

When the propeller shaft and the auxiliary motor are connected in reciprocal driving relation, it is possible to dive with both motors shut off and to have the gearing such that the propeller turning at speeds too slow to start the main propelling motor, will nevertheless spin the auxiliary motor at speeds sufficient to start it, and the latter upon starting will in turn speed up the main motor to its starting speed.

The above functions, particularly the feature of having the auxiliary motor in reciprocal relation to the main motor may be usefully employed on high power trucks, automobiles, etc. In such case, the auxiliary motor may be started by hand and used to start the main motor. The auxiliary motor may be continued in operation or may be cut off during the run. In the latter case the clutch may be thrown in and the auxiliary motor started just before the vehicle is brought to a standstill. The main motor may then be stopped and the auxiliary motor allowed to idle until such time as it is desired to re-start the vehicle, whereupon the clutch may be thrown in and the main motor started.

A desirable embodiment of my invention is shown in the accompanying drawings, in which—

Figure 1 is a top plan view diagrammatically indicating the relative arrangement of parts constituting my present invention; Fig. 2 is a view of the motors and transmission mechanism, the motors being indicated in plan outline and the transmission in horizontal section;

Fig. 3 is a view showing an arrangement

of overrunning clutches which may be employed in the transmission shown in Fig. 2.

The aeroplane 1 is provided with an internal combustion motor 2 of any known or desired construction, adapted to drive the propeller 3 which is rigidly secured upon the propeller shaft 4. The latter is customarily a rigid extension of the crank shaft of the propelling motor. On the other end of said crank shaft is the fly wheel 5.

The auxiliary motor 6 is an internal combustion engine preferably of small size and preferably air cooled. Certain well-known types of motor cycle engines are suitable for this purpose.

The auxiliary motor may be connected to rotate the shaft 4 and the fly wheel 5 and intervening crank shaft to the main motor through any suitable transmission connections. As shown in the drawings, the auxiliary motor 6 has its crank shaft 7 provided with a small gear 8 meshing with a larger gear 9 on shaft 10 carrying pinion 11, adapted to mesh with gear 12 mounted on shaft 4.

Preferably, however, the gear 12 is loose upon shaft 4 and adapted to be connected thereto through the medium of a friction clutch. One member of this clutch is shown as a hollow cone member 13 integral with gear 12. The other clutch member is the cone 14 keyed to but slidably mounted on shaft 4 and adapted to be forced into and out of frictional engagement with the hollow cone 13 by any suitable controlling or operating mechanism. This is indicated by the slip collar 15, lever 16, pivoted at 17 on bracket 18 and connected to an operating member 19.

When it is desired that the main driving motor 2 be capable of transmitting its power to drive the auxiliary motor 6, I provide a pinion 20 adapted to be driven by shaft 4 and meshing with gear 21 on shaft 10. Preferably the gear 20 is integral with gear 12 and clutch member 13.

The gear 21 is provided with an overrunning clutch device adapted to grip shaft 10 to transmit power from shaft 4 to shaft 10 but to slip when power is applied in the opposite direction from shaft 10 toward shaft 4.

The arrangement of overrunning clutches for connecting and disconnecting pinion 11 and gear 21 is clearly indicated in Fig. 3. When the shaft 10 is driven in the direction of the arrow and the pinion 11 is retarded, as when motor 2 is not operating, the rolling cylinders 22, 22 will wedge between the periphery of the shaft 10 and the cam surfaces 23, 23 of the recesses in which they are located. Whenever the pinion 11 speeds up or the shaft 10 slows down the cylinders are rolled backward toward the large end of their respective recesses and hence will not

transmit any power from pinion 11 to shaft 10. The gear 21 has recesses and rolling cylinders 24, 24, 24, exactly like 22 and 23 of gear 11, except that the inclined surfaces 5 are reversely arranged. Hence, when the shaft 10 is rotating at a speed to drive the pinion 11, it will roll the cylinder 24 toward the larger end of the recesses where they will not bind and will not transmit power. Similarly 10 when the direction of power transmission is reversed and the cylinders 22 slip, the cylinders 24 will grip. It will be understood that the direction of transmission of power depends entirely upon the relative 15 speeds, since the parts never reverse but rotate only in one direction as indicated by the arrows.

It will be noted that in the proportion 20 shown, gear 9 has about 1 revolution for every 2 revolutions of gear 7 and that gear 12 has about 6 revolutions for 1 revolution of pinion 11 so that in the proportion shown, the auxiliary motor 6 will be capable of driving the main motor 2 at approximately one-twelfth 25 the speed of said auxiliary motor. It will also be noted in the proportions shown the gear 21 rotates about half as fast as gear 20 and gear 7 rotates about twice as fast as gear 9, so that when the main motor 30 2 drives the auxiliary motor 6, their revolutions per minute are substantially the same.

It will be understood, however, that the speed transmission ratios in both directions 35 may be widely varied from those above indicated and it may be found useful to arrange the gearing so that main motor 2 will drive auxiliary motor 6 at rates much less than those of said main motor.

While there is a peculiar inter-relation 40 and combination of the above described auxiliary motor and power transmitting connections in combination with an aeroplane in which the propeller is rigidly connected to the main motor shaft, making it possible to 45 utilize the head pressure on the propeller to rotate and start the auxiliary motor, it is obvious that the parts shown in Fig. 2 are capable of useful employment in the various other relations and for the other purposes 50 hereinabove indicated.

While I have shown and described a preferred form of my device, it will be obvious 55 that various omissions and substitutions of parts may be made by those skilled in the art, as for instance, the gear 12 may be locked to the shaft 4 directly instead of through the medium of the friction clutch 14, and where such clutch is used it is not necessary to use an overrunning clutch for 60 locking the gear 11 to the shaft 10.

I claim:

1. A screw propelled flying machine and motive means therefor, including two internal combustion motors, one large and the 65 other small and independently energized, in

combination with means whereby said motors may be operated either simultaneously or independently or in reciprocal driving relation so that the small motor may be started independently and utilized as a 70 starter and idler for the large motor, and may be restarted from the crank shaft of the latter.

2. A motor vehicle and motive means therefor including two internal combustion 75 motors, one large and the other small, in combination with means including a friction clutch and power multiplying speed reducing gearing between the large motor and the small motor whereby the small motor at its normal speed may drive the large motor at its starting speed and means including an overrunning clutch for preventing the large motor at its normal speed from driving the small motor at speeds exceeding 80 its maximum safe running speed.

3. A motor vehicle and motive means therefor, including two internal combustion motors, one large and one small, in combination with reciprocal power transmitting 90 connections whereby the large motor may drive the small motor at a desired speed and the small motor may drive the large motor at much less speed.

4. A motor vehicle and motive means 95 therefor including two internal combustion motors, one large and one small, in combination with reciprocal power transmitting connections whereby the small motor at normal speed may drive the large motor at 100 starting speed and whereby the large motor at normal speed may drive the small motor at a speed sufficient for starting the small motor but not exceeding its maximum safe running speed.

5. A motor vehicle and motive means therefor including two internal combustion 105 motors, one large and one small, in combination with reciprocal power transmitting connections including a friction clutch, 110 whereby the large motor may drive the small motor at a desired speed and the small motor may drive the large motor at much less speed.

6. A motor vehicle and motive means 115 therefor including two internal combustion motors, one large and one small, in combination with reciprocal power transmitting connections including two sets of gearing and overrunning clutches for each, whereby 120 the large motor may drive the small motor at a desired speed and the small motor may drive the large motor at much less speed.

7. A flying machine and motive means 125 therefor including an internal combustion motor, a screw propeller rigidly connected with the crank shaft of said motor whereby air pressure on the propeller may be utilized to spin the motor, in combination with an auxiliary internal combustion motor and 130

power transmitting connections including two sets of gearing, overrunning clutches in each set, and a friction clutch for both sets, whereby said auxiliary motor at normal speed may drive said first mentioned motor at starting speeds and whereby power from said main motor or from said propeller may

be utilized to spin said auxiliary motor at speeds sufficient for starting but not exceeding its maximum safe running speed. 10

Signed at New York city, in the county of New York and State of New York, this 31st day of December, A. D. 1917.
